DELBERT W. BUTZ AND MOTT M. UITTS, OF KOKOMO, INDIANA

KNOCKDOWN VARIABLE-UNIT CABINET

Application filed March 1, 1926. Serial No. 91,499.

This invention relates to a knock-down and variable unit cabinet.

One object of this invention is to construct a cabinet of a plurality of units so associated together in abuttable or spaced relation, or in abuttable and spaced relation as required, and suitably secured together so that the entire construction, when assembled, will not only give the appearance of being but substantially 10 is a custom built unitary cabinet.

Another object of the invention is to construct the cabinet of a plurality of units each of which is of knock-down construction so that each unit may be collapsed into knock- 15 down arrangement and individually packaged for shipment or storage, or both.

One feature of the invention consists in the construction of a minimum number of cabinet units of different types and sizes 20 and unit connecting members in the form of mullions, tops and bottoms permitting the judicious selection of the units both as to number and type required, to which may be added in certain instances, a splash board, the individual splash board, bottom or toe-board and top each being of a length sufficient to cover, align or unite all of the units selected into an entirety as a custom built cabinet.

Another feature of the invention consists 30 in the construction of each of the several units and also the ends and the connections between the units, or unit and end in knock-down arrangement, whereby the several parts can be collapsed for individual packaging and subsequent shipment or storage, whereby unit 35 assembling can only be secured through predetermined positioning of the several parts of the unit, and such predetermined positioning is of the simplest character and requires 40 little or no skill and the use of but a hammer or screw driver, or both, and whereby the units, ends and toe-board are similarly connected.

While the number of units manufactured 45 may be innumerable, it has been determined from past experience in building custom built cabinets that a certain minimum number of units will satisfactorily solve substantially all 50 construction problems and this minimum

number is six, of which three are of the same type but differ only in width.

The foregoing invention permits the dealer, jobber or contractor to carry on display but six units which can be arranged as desired. 55 The particular problem can be solved by the judicious selection of the several units or by multiplications of units. In each construction the toe-board, top, and if desired, the splash board, is of the desired over-all length 60 for uniting and connecting the unitized cabinet units.

The full nature of the invention will be understood from the accompanying drawings and the following description and 65 claims:

In the drawings Fig. 1 is a top plan view of a cabinet including a splash board, said cabinet extending entirely along one wall of a room and being included between two side 70 walls thereof. Fig. 2 is a front elevation thereof. Fig. 3 is a front elevation of one of the drawer units and of the small width single tier type. Fig. 4 is a front elevation of one of the cabinet units and of the small 75 width single door type. Fig. 5 is a side elevation of any one of the units. Fig. 6 is a perspective view of an end panel. Fig. 7 is a perspective view of the mullion or vertical unit connecting member. Fig. 8 is a front 80 view of a multiple drawer cabinet unit. Fig. 9 is a perspective view of the intermediate portion of the toe-board construction, parts being broken away. Fig. 10 is a front elevational view of a multiple door cabinet unit. 85 Fig. 11 is a top plan view of a cabinet positioned in the end of a room and herein the right-hand end or corner thereof. Fig. 12 is an enlarged transverse or horizontal section of the cabinet shown in Fig. 11, parts being broken away to illustrate the knock-down construction and arrangement. Fig. 13 is a front to rear vertical sectional view through the bottom of any of the cabinet units when 90 mounted in cabinet formation and is taken on line 13—13 of Fig. 12 and in the direction of the arrows. Fig. 14 is a perspective view of the corner mullion or end panel and unit connecting member. Fig. 15 is a transverse sectional view of a drawer slide mounting and is 95 100

taken on line 15—15 of Fig. 12 and in the direction of the arrows. Fig. 16 is a similar view of a partition with drawer slides mounted on opposite sides and is taken on line 16—
16 of Fig. 12 and in the direction of the arrows. Fig. 17 is a transverse sectional view of any unit taken in plane 17—17 of Fig. 12 and in the direction of the arrows.

This invention is directed to the construction of cabinet units of a type which readily lend themselves to multiplication and adjustment so that they can be secured in cabinet formation by the addition of but a few simple parts which permit quantity production of but a minimum number of standard parts and the use of but a minimum number of variable parts for any installation or formation of a cabinet for a particular position or arrangement. The foregoing permits the combination of various widths of units with variable allowable spreads between each to form practically any desired type of cabinet ranging in width from a minimum of approximately eighteen inches to an unlimited number of feet or fractions thereof, the variations in width being any difference therebetween as will be more apparent from the subsequent description. In addition to the foregoing, each of the units is of knock-down construction, whereby each unit can be packaged individually and shipped flat, thereby reducing storage and transportation space and expense to a minimum. The knock-down arrangement is of such character that parts of each unit can only be assembled in a predetermined way.

Before proceeding to a detailed description of the knock-down construction of each unit and the details of the connection between the several units when assembled in unit formation, two typical cabinets will be described and the units comprising the same.

In Figs. 1 and 2, 10 indicates a back wall and 11 the side wall of a room. A top 12 and a toe-board construction 13, and herein a splash board 14 are co-extensive with the back wall 10 and extend from one side wall to the other. The foregoing are the only portions of the entire construction which are not sectionalized or unitized and these are generally furnished in such lengths that they may be readily cut to length without much wastage. As the window or other conformation of the room determines the position of the sink, indicated generally by the numeral 15 in Fig. 2, said sink position permits the carpenter installing the cabinet to cut the opening indicated by the numeral 16, in the top to receive the sink 15. This may be done before or after the top has been mounted, but it will be understood that each opening 16 in the top 12 conforms to each specific cabinet installation when a sink is employed. There are practically as many uses, or more, for the cabinet construction

where a sink is not employed, and in these instances the opening 16 will not be cut in the top.

In Figs. 1 and 2 but three different units are shown. Herein a single tier of drawers unit is indicated generally by the numeral 17, the multiple tier of drawers unit divided by a partition and including a bread and meat board, is indicated by the numeral 18 and the double door units are indicated by the numeral 19.

Fig. 3 illustrates the single tier of drawers unit 17. Fig. 8 illustrates the double tier of drawers unit 18, and Fig. 10 illustrates the double door unit 19. 20 indicates generally the single door unit shown in Fig. 4. It will be understood that sinks vary in arrangement. Thus, the type of sink shown in Fig. 11 contains a bowl portion smaller than that shown in Figs. 1 and 2 but also includes a drain board portion. Thus, the opening 116 required for the sink of the type shown in Fig. 11 and indicated by the numeral 115 therein, is larger than that shown in Fig. 1. Also smaller sinks may be utilized. Therefore, cabinets indicated by the numeral 19 in the several figures and particularly illustrated in Fig. 10, are preferably made of three sizes, each having the same depth from front to rear and the same height but varying in width. Door panels, therefore, vary according to the size of the units. The doors are so arranged that complete access may be had to the plumbing connecting with the sink. Shelving may also be provided if desired.

In Fig. 3 the unit comprises the two sides, the front and a plurality of superposed drawers. In Fig. 4 the unit comprises a compartment closed by a single door. In Fig. 8 the unit 18 comprises a plurality of tiers of superposed drawers and in addition includes a bread or meat board 118. Fig. 5 illustrates the left side of any unit 40, having the top edge or face 41, the back edge or face 42, the front edge or face 43, the bottom edge or face 44 and a notched or cut out arrangement 45 and 46. The end panel 30 (see Fig. 6) when required such as in the installation shown in Fig. 11, has a lower corner cut out as at 35 and 36, the top edge 31, the back edge 32, front edge 33 and bottom edge 34. The corner cut out 35—36 is of less size than the corner cut out 45—46 formed in each unit 40. A mullion or spacer strip 37 is shown in Fig. 7 and this is of a standard width, that is has a spread of five inches. It will be understood that but a single width of spacer, mullion, or connector 37 is furnished and the carpenter or assembler of the cabinet can cut this member to the desired width, the length being constant, and the thickness being constant, the width being determined by the amount of spread or spacing to be employed between the sev-

eral units in order to take up the total space allotted to the cabinet.

As shown in Figs. 1, 2, 11 and 12 the bottom construction 13—113 extends throughout or is coextensive with the length of the cabinet and the particular construction of the same includes the riser 13 and lateral 133, see Fig. 9, the same showing the toe-board or base in perspective.

Fig. 11 shows a cabinet positioned in the right-hand corner of the room, and therefore, provided with an end panel 30. This cabinet is so arranged that the sink including the drain board is at the extreme right end and, therefore, a double door unit 19 is employed at this end. For kitchen purposes the unit 18 (Fig. 8) is preferred and herein is shown positioned immediately adjacent the sink enclosing unit 19. Adjacent thereto in order to complete the cabinet and occupy the allotted space is a smaller unit which herein is shown as a single door unit 20. The cabinet consists of units 18, 19 and 20, with unit 18 positioned in the middle, panel 30 at the exposed end, top 12 and toe-board 13—113.

Fig. 12 is an enlarged longitudinal sectional view of the left-hand portion of the cabinet shown in Fig. 11 and is taken in a plane parallel to the top. Each unit has a back 50 which extends from the top 12 to and rests upon the floor. Each side 40, except for the notched corner, see Fig. 5, extends from the top 12 to and rests upon the floor. Back 50 is provided with an upper cleat not shown and a parallel cleat 51, the top of which lies in the same horizontal plane as the top of the toe-board 13—113, although it may lie in another plane as side 40 has a similar cleat 47, see Fig. 17, that is, one which lies in the same plane as cleat 51 to vertical and parallel cleat 53. The opposite edges of the back 50 including vertical cleats 53 form grooves with the upper (not shown) and lower cleats 51 to receive the edges 42 of the sides 40 which are thus seated, and maintained in parallel position at the top and bottom at the rear of each unit (see Fig. 12).

The front of the cabinet unit includes a rectangular framework, the upper portion of which supports a transverse cleat not shown, but which is parallel to the bottom rail 57 of the front 56. The front carries, in slightly offset relation to the outer and lateral edges, the vertical cleats 54 which form a groove including therebetween the front top cleat not shown. Each side 40 carries a cleat at its outer edge that abuts the front and is seatable with said side in the groove previously described. This cleat upon the outer edge of the side also abuts the top cleat of the back.

The resultant construction, therefore, is a true rectangular compartment or open

unit having no bottom, no top and having the lower front corner cut out, the front panel being suitably formed either for a door or for drawers. A bottom 52 is adapted to be positioned in the compartment thus formed and to rest upon the two side supported bottom rails 47 and the back supported bottom rail 51. When in this position the bottom 52 lies flush with the bottom rail 57 of the front (see Fig. 12). The foregoing, therefore, constitutes one of the units in assembled relation, the top being open and the bottom being closed. The two screws or securing means near the ends of the cleats 54 are sufficient to anchor the front edge of a side to the front and two screws or the like at the ends of the cleats 53 are sufficient to anchor the rear edge of the side to the back. The bottom thus maintains the unit when in assembled relation, in true rectangular form and prevents its collapse. It will be readily apparent that with the foregoing construction each unit can be assembled and disassembled and when in the latter condition, the back, front, two sides and bottom can be positioned in parallel and superposed relation and cartoned for shipment or storage in the flat or knock-down condition.

The front 56 has lateral or side extensions 58 which are vertically grooved as at 59. The mullion or connecting strip 37 is receivable by two adjacent grooves 59 in adjacent but oppositely positioned lateral extensions 58 of adjacent units. The front, including the lateral extensions 58 and the bottom piece 57, is cut out as at 60 and thus the angular toe-board 13—113 has its front edge covered by the front of each unit. The front edge of the toe-board, however, is exposed whenever the two adjacent members 58 are not in abuttable relation as shown to the right of Fig. 12, the spaced relation being shown to the left of Fig. 12. When in abuttable relation, the front edge of the toe-board construction is entirely covered or non-exposed and member 37 suitably reduced in width to be receivable by the adjacent grooves 59, serves solely as a spline and does not serve as a mullion. The end panel 30 has its lateral edge 32 terminating short of the back of the unit. The end panel 30 has its front edge 33 terminating adjacent the extension 58. The side of the panel is adapted to abut the vertical cleats 53 and 54.

An angular cornice or ornamental member has a main body portion 137 and a tongue portion 38. Tongue portion 38 is either receivable by the slot or groove 59 or over-lies the end 32 of the end panel and abuts the back 50 forming an ornamental corner. The two screws associated with each cornice near the upper and lower ends thereof are adapted to secure the cornice and end panel to the adjacent unit side in completed relation. The

cornice pieces are furnished in two lengths, the rear cornice piece being of the height of the unit, that is, extending from the floor to the top and the front cornice piece (having the portion seatable in the groove 59) 5 extending from the top to the lower level of the lateral portion 113 of the toe-board. The units, however, may be supplied in equal lengths and generally only two will be required, although if the cabinet is of the 10 isolated type, that is has two exposed ends, four of the cornice members are supplied and two similar end panels are supplied. The end panels, of course, are reversible, that is, 15 they will serve equally well for the left-hand end as for the right-hand end.

It is to be understood that all of the parts are drilled in jigs and the necessary number of securing screws, nails or the like are supplied with each unit so that the assembling is 20 reduced to a minimum and is of a character that prevents any assembling arrangement other than the necessary one to form the unit.

25 Each drawer unit side 40 carries the drawer slide or cleat 61. This is shown clearly in Fig. 15. When shelving is required, the door unit side 40 would be provided with the cleat 61 and the shelving would be supplied 30 as additions and in the number desired. In a tandem drawer unit there is provided a partition 62 which upon opposite sides supports the drawer slide members 63 which are cut out as at 64 to form a drawer slide supporting surface. The front of a unit of the aforesaid type includes a vertical member 65 with an inwardly extending cleat portion 66. The partition 62 is adapted to be slidably receivable between another cleat 166 on the back 50 and the inner face of the cleat 66. 35 Lateral displacement of the partition 62 is prevented by the forward and rearward extensions 67 and 167 of the drawer slide members 63 beyond the cleats 66 and 166 as shown 40 clearly in Fig. 12. The rear cleat 166 on the member 50 may be suitably recessed to receive the bottom 52.

Drawers have heretofore been made and shipped knock-down and therefore are not 50 illustrated herein. The doors are flat panels with the necessary hardware attached thereto, or the necessary hardware is supplied in detached relation and the doors are drilled or otherwise formed to receive said hardware.

55 With the foregoing construction several different types of units may each be formed in the knock-down and packaged for storage or shipment in such formation and thereafter 60 readily assembled to form the compartment which is entirely unitized except for the cover.

From the foregoing description and the 65 drawings it will be noted that it is impossible to assemble any unit in any other way

than in the predetermined proper arrangement. Confusion between parts will be entirely eliminated if each individual package containing a complete unit is opened and assembled before opening any other package. 70 It will be also noted that each unit when in disassembled relation is a completely closed construction except for the top and therefore a rat hole in any one unit will not give access to the other units but only to that one containing the hole. 75

Figs. 1 and 11 show the several cabinet units secured together in spaced or spread joint relation and butt joint relation, said connections being secured by the splining or mullion strips 37 retained in position against upward displacement by the tops and against downward displacement in the grooves 59 by resting upon the toe-board construction. The units are secured in 80 spaced relation by the toe-board construction being secured preferably to the front exposed edges 46 of each of the sides 40. When thus secured each unit is definitely positioned with respect to the other units also 85 secured to the toe-board. The common top also serves to secure all of the units together and serves to close the same forming individual completely closed compartments with the result that the unitized cabinet, although 90 formed from separable standard units, resembles very closely and approximates the custom built cabinet.

95 The foregoing invention reduces the erection of the cabinet to a minimum and by the use of but six standardized units, one end panel, one mullion or spline member and one cornice, the variable mill work is reduced to the minimum. The only variables are adjusting the width of the mullion to the desired spread or space, cutting the length of the top, splash and toe boards to the desired length of the entire cabinet and reducing one or two of the standard cornice members to the sub-standard length described providing the two cornice members are not of dissimilar length. 100

105 The foregoing arrangement permits the mill work in cabinet units and other parts of the invention specified to be performed 110 during the slack seasons, thereby further reducing the lowered cost made possible by the quantity production of a small number of different standard cabinet units. The cabinet constructions possible with the foregoing invention are suitable for the kitchen, 115 bath rooms, barber shops, sales rooms and in general wherever custom built cabinet work of the character herein generally disclosed is required. 120

125 The foregoing invention has the additional advantage that it is not a fixture and can be readily disassembled and removed to a new location and reassembled in the same or a different relation as required by the new 130

location, the only difference being that if the top has been cut for a sink a new top may be required and generally will be required. The result, therefore, is a portable construction which resembles the built-in or fixture construction in all of its advantages and with little or none of its disadvantages.

5 The invention claimed is:

10 1. A knockdown cabinet unit including a front frame member having side edges, vertical cleat means at each side edge thereof forming a groove therebetween, a back member having side edges, vertical cleat means on each side edge thereof, lateral means on said back member terminating adjacent each vertical cleat means on the back member and forming grooves therewith, and a pair of side members, each having its front and rear edges detachably received by said 20 grooves.

25 2. A device of the character defined by claim 1, characterized by the addition of a bottom member peripherally enclosed by the side, back and front members for maintaining said members in quadrilateral relation and supported thereby.

In witness whereof, we have hereunto affixed our signatures.

30 DELBERT W. BUTZ.
